MAILING CARD

Arthur Podmore, London, England

Application December 27, 1938, Serial No. 247,981
In Great Britain December 31, 1937

6 Claims. (Cl. 46—35)

This invention relates to mailing or postal cards of the type known as letter-cards and has for its object the provision of an improved letter-card incorporating a picture or view such as a 5 land or seascape or other pictorial representation which is arranged in an attractive and novel manner.

The invention consists in a letter-card having a number of integral or attached adjacent picture sections or strips which lie flat on each 10 other for storage, or for transit through the post, and are adapted to be moved into spaced relationship in planes parallel to one of the panels of the card to form a composite picture.

15 The invention further consists in a letter-card comprising a rear panel hingedly connected to an end panel (or panels), a picture section or sections connected to the end panel (or panels) so as to be movable to a position away from the 20 rear panel when the end panel (or panels) is moved at right angles (or other suitable angle) to the rear panel, and a cover panel hingedly connected to one end panel in a readily removable manner.

25 Means may be provided for temporarily securing the cover panel to the rear panel when the card is in the collapsed condition, such means preferably comprising tongues on the cover panel and corresponding slits in the rear panel.

30 The end panels may be connected by a frame element through which the picture is adapted to be viewed.

The composite picture may comprise a section mounted or impressed upon the rear panel, and 35 one or more forward sections located between the rear section and said frame, said frame also if desired including a section of the picture.

The accompanying drawings illustrate a letter-card according to the invention,

40 Figure 1 being a perspective view with the cover panel opened and the card erected;

Figure 2 is a view with the card collapsed;

Figure 3 is a plan view with the card in open or erected condition;

45 Figure 4 is a section on the line 4—4 of Figure 2;

Figure 5 is a developed view showing a one piece blank for forming the card.

In carrying the invention into effect according to one convenient mode by way of example, the letter-card is formed from a suitable paper or card and comprises four panels, viz., a rear panel 5, two end panels 6 and 7 hingedly connected to the rear panel, and a cover panel 8 50 hingedly connected to the left hand end panel 6.

The hinging may be effected by suitably scoring the material, or hinge strips may be applied thereto. When the card is in a collapsed or flat condition (see Figure 2) the free edge 8a of the cover panel 8 is adapted to lie contiguous to the 5 edge 7a of the right hand end panel 7.

Mounted on the inner face of the rear panel 5, or suitably impressed thereon as by printing, is a section of the panoramic view. This section 10 comprises the upper portion of the picture and occupies the full width of the rear panel, extending from one end panel 6 to the other 7 or may include such panels. Mounted forwardly of the rear panel and hingedly connected to the end panels is a pair of sections of the picture, 15 namely an intermediate section 9 and a forward section 10. The intermediate section 9 comprises the central portion of the panoramic view while the forward section 10 comprises the lower portion of the picture. The intermediate section 20 rises a suitable distance above the lower section according to the view being displayed. The forward and intermediate sections are cut out so that they form silhouettes of the portions of the view. The intermediate and forward sections 25 are suitably hinged to the end panels.

The forward section 10 of the picture is combined with a frame element 11 which is hinged in any suitable manner to the forward edges of the end panels 6 and 7. The frame element 11 30 provides a window through which the upper portions of the composite picture are adapted to be viewed.

The frame 11 at its upper and lower edges is provided with cut-out parts 12 and 13 to expose 35 upper and lower marginal portions of the rear panel. Located in these exposed upper and lower marginal portions of the rear panel are slots 16 and 17 which are adapted to accommodate tongue portions 14 and 15 formed on the cover panel 8 when the card is collapsed, such tongues and slots forming a temporary fastening means for holding the cover panel in position. Instead of the tongue and slot fastenings any other suitable means may be provided for securing the cover 40 panel to the rear panel along the upper and lower edges. Thus, gummed marginal portions may be provided on either the rear panel or the cover panel after the manner of the gummed tear-off margins known in letter-cards, or such 45 tear-off margins may be provided with self sealing adhesive.

In addition to the temporary securing means the cover panel 8 is adapted to be secured (when the card is collapsed) by the postage stamp 55

which is adapted to lie half over the cover panel and the other half over the adjacent end panel 7. Obviously, instead of, or in addition to, the sealing by a postage stamp, an adhesive strip 5 and/or a tongue and slots may be applied.

The upper marginal portion 7b of the right hand end panel 7 is adapted to be hinged (by scoring the card at 7c) to the main part of said panel so that when the card is erected to display 10 the view such marginal portion may be bent downwardly and inwardly between the rear panel 5 and frame 11 to hold the parts in the display position. When the card is to be displayed it is preferred to remove the cover panel 8, for which 15 purpose at the hinge joint between the cover panel and the adjacent end panel a row of perforations may be provided whereby the cover panel may be readily torn off. The cover panel 8 is adapted to be used for correspondence on 20 its inner surface and if desired a number of sheets may be attached thereto. On its outer face the cover panel is adapted to be used for the name and address of the addressee.

Conveniently the card is formed from a single 25 strip as indicated in developed view in Figure 5 in which the cover panel 8, rear panel 5, combined frame and front portion of the picture 11, and the intermediate portion of the picture 9, are connected together by the end panels 6 and 7 and 30 hinging panels 18 and 19. The latter are adapted to be gummed to the end panels 6 and 7 (see Figure 3) to hold the intermediate picture section 9 in correct relation with regard to the other parts.

35 The various panels are hinged to one another by suitable scoring or perforated lines 20.

Obviously instead of forming the card from a single strip or blank two or more strips may be used, as may be found convenient in manufacture.

40 Instead of forming the front portion of the picture in one with the frame element 11 such portion may comprise a further intermediate section, and in this case the frame could be provided 45 with a transparent panel if desired.

Where two intermediate sections of the picture are provided they would be displaced at suitable distances from the rear panel.

Instead of providing a pair of end panels only 50 one may be used, in which case the intermediate picture section at one end will be secured to such panel while at the other end or adjacent such end a hinging portion securing it to the rear panel is provided. This hinging portion may be provided with a bending part similar to 7b for holding the parts erected.

55 With such an arrangement the front cover panel will be of a length equal to the combined lengths of the rear panel and end panel so that 60 the free edge of the cover panel reaches to the free edge of the rear panel when the card is collapsed. The temporary securing of such free edges may be effected by removable gummed strips.

65 While in the above described card the forward and intermediate sections of the picture are such that the intermediate portion is exposed above the front portion and the rear portion is exposed above the intermediate portion, the position 70 may be reversed according to the nature of the picture to be displayed.

As above described, the picture sections or strips lie parallel to the longitudinal dimensions of the letter-card; they may however lie transversely thereto, in which case the end panels will

be hinged to the long edges of the rear panel so that the composite picture is viewed with said long edges vertical.

It will be appreciated that a suitable overlap will be provided between the intermediate section of the picture and the upper and lower sections respectively so that there are no gaps in the composite picture.

By means of the invention a picture letter-card is provided in which the picture is presented in an attractive manner and setting.

I claim:

1. A collapsible picture card comprising a rear panel hingedly connected to end panels, said rear panel forming a rear section of a composite picture, an intermediate picture section connected to said end panels, a frame element connected to the end panels and comprising a front picture section said rear panel, intermediate picture section and frame element always lying in parallel planes, a cover panel hingedly connected to an end panel in a readily detachable manner, said panels and sections all being formed as a one-piece blank.

2. A collapsible picture card comprising a rear 25 panel hingedly connected to end panels, said rear panel forming a rear section of a composite picture, an intermediate picture section connected to said end panels, a frame element connected to the end panels and comprising a front 30 picture section, a cover panel hingedly connected to an end panel in a readily detachable manner, said panels and sections all being formed as a one-piece blank, said rear panel having slots adjacent two opposed edges, said cover panel having 35 tongues adapted to engage in said slots when the card is in the collapsed condition for temporarily securing the cover panel to the rear panel adjacent said edges, said frame element having opposed edges cut away to expose said slots.

3. A collapsible picture card comprising a rear panel hingedly connected to end panels, a picture section connected to said end panels so as to be movable to a position away from the rear panel when the end panels are moved at right-angles 45 to the rear panel, a cover panel hingedly connected to an end panel in a readily removable manner and means for temporarily securing the cover panel to the rear panel adjacent the free 50 edges thereof when the card is in the collapsed condition.

4. A collapsible picture card comprising a rear panel hingedly connected to end panels, a picture section connected to said end panels so as to be movable to a position away from the rear panel 55 when the end panels are moved at right-angles to the rear panel, a cover panel hingedly connected to an end panel in a readily removable manner, said rear panel having slots adjacent two opposed edges, and said cover panel having tongues 60 adapted to engage in said slots when the card is in the collapsed condition for temporarily securing the cover panel to the rear panel adjacent said edges.

5. A collapsible picture card comprising a rear panel hingedly connected to end panels, and forming a rear section of a composite picture, an intermediate picture section hingedly connected to said end panels, a frame element hingedly connected to the end panels and comprising a front picture section, a cover panel hingedly connected to an end panel in a readily detachable manner and strut means adapted to lie between the frame section and rear panel for holding the picture sec- 75

tions in spaced relation when the card is in the display condition.

6. A collapsible picture card comprising a rear panel hingedly connected to end panels, and forming a rear section of a composite picture, an intermediate picture section hingedly connected to said end panels, a frame element hingedly connected to the end panels and comprising a front picture section, a cover panel hingedly con-
- nected to an end panel in a readily detachable manner and means for holding the picture sections in spaced relation when the card is in the display condition, said means comprising a hinging portion of an end panel adapted to be moved 5 into a plane at an angle to said end panel and to lie between the rear panel and frame element.

ARTHUR PODMORE.
